UNITED STATES PATENT OFFICE.

HYMAN RUBIN, OF BROOKLYN, NEW YORK.

FOLDER FOR SEWING-MACHINES.

1,230,036.

Specification of Letters Patent. Patented June 12, 1917.

Application filed September 12, 1916. Serial No. 119,661.

To all whom it may concern:

Be it known that I, HYMAN RUBIN, a citizen of the United States, and a resident of the city of New York, borough of Brooklyn, in the county of Kings and State of New York, have invented a new and Improved Folder for Sewing-Machines, of which the following is a full, clear, and exact description.

10 My invention relates to folders for sewing machines. The object thereof is to provide an adjustable folder whereby the same can be used for various widths of bindings.

With the above and other objects in view, 15 the nature of which will more fully appear as the description proceeds, the invention consists in the novel construction, combination and arrangement of parts as herein fully described, illustrated and claimed.

20 In the accompanying drawing, forming part of the application, similar characters of reference indicate corresponding parts in all the views.

Figure 1 is a plan view of a folder embodying my invention;

Fig. 2 is a side elevation thereof;

Fig. 3 is a cross section on line 3—3, Fig. 1;

Fig. 4 is an elevation from the opposite 30 side of that shown in Fig. 2; and

Fig. 5 is a section through fabric trimmed by means of my device.

Referring to the drawings, 5 is a slotted arm whereby the folder may be secured to 35 a sewing machine. It has a body portion 6 which carries one section 7 of the guiding member 8. The other section 9 of the guiding member, which is separated from section 7, has a body portion 10 coöperating 40 with the body portion 6. The two sections 7 and 9 are maintained in proper register by a pair of guiding pins 11 carried by the body portion 6 and projecting through the body portion 10. They are also guided at 45 the inlet to the guide 8 by flanges 15 extending from each section toward the other,

the section 9 having its flange in the front, while the section 7 has its flange in the rear. Coil springs 12 are mounted on said pins. The ends of said coil spring are nested in the body portions 6 and 10. The tendency of said spring is to normally separate the guide sections 7 and 9. This is resisted by a set screw 13 having a knurled head which passes through the body portion 10 and is threaded in the body portion 6. By means of this set screw the distance between the sections 7 and 9 may be adjusted and, therefore, different widths of binding can be used. The lower guide section 7 has 60 a plate 14 which guides the goods to be bound between the folded binder.

It will be noted that the guide 8 is formed of two independent sections 7 and 9 which normally tend to separate under 65 the action of the coil springs 12 but are resisted by the set screw 13. The guide sections taper gradually from the receiving end toward the delivery end, as is common in this class of devices, to fold a strip upon 70 its intermediate edges as it passes through the guide. The guide sections are so arranged as to fold the strip passing therethrough twice, consequently presenting a clean edge A to the fabric B to be bound 75 by C (see Fig. 5).

I claim:

In a folder, a guide for strips to be folded having two independent guide sections each adapted to fold one edge of a strip, 80 a body portion associated with each of said guide sections, pins carried by one of said body portions and engaging the other of said body portions whereby the two guide sections are maintained in proper register, 85 coil springs on the pins between the body portions normally tending to separate the guide sections, and a set screw binding the two body portions whereby the distance between the sections may be adjusted for 90 various widths of strips to be folded.

HYMAN RUBIN.

Copies of this patent may be obtained for five cents each, by addressing the "Commissioner of Patents, Washington, D. C."
